UNITED STATES PATENT OFFICE.

HAROLD A. WIBERG, OF NEW YORK, N. Y.

RECORD-CABINET.

1,351,596.

Specification of Letters Patent. Patented Aug. 31, 1920.

Application filed October 8, 1919. Serial No. 329,307.

To all whom it may concern:

Be it known that I, HAROLD A. WIBERG, a subject of the King of Sweden, residing at New York, in the county of Bronx and State 5 of New York, have invented certain new and useful Improvements in Record-Cabinets, of which the following is a specification, reference being had to the accompanying drawings.

10 This invention relates to an improved record cabinet, and an object of the invention is to provide a very simple, inexpensive and practical device of this kind capable of being manufactured for a relatively low 15 cost and sold at a reasonable profit.

Another object of the invention is to provide a record cabinet including an improved record labeling means used in conjunction with a chart or index so that any one of the 20 records may be easily selected, without going over the various records until the one which is desired is found.

Furthermore, it is the aim to provide a record designating means including strands of cord connected to a support in the cabinet and having numbered loops to engage correspondingly numbered hooks carried by the support, so as to hold the records in place 25 in the cabinet, by passing the strands of cord through the apertures in the centers of the records, and connecting the numbered loops to the correspondingly numbered hooks.

A still further object of the invention is 30 the provision of means mounted upon elastic members on the lower part of the cabinet to be engaged by the loops of the strands of cord, to hold the loops and the cords in position, so that the loops will be in position to 35 be re-inserted through the apertures or openings of the records when replacing the records in the cabinet.

An additional object of the invention is to 40 provide a cabinet having an inclined bottom, downwardly upon which the record rolls, when the cord is detached from its respective hook, so that the record will be in position to be grasped by the hand, and when 45 the cord is removed through the aperture or opening of the record, the loop of the cord 50 is connected to a hook mounted upon the elastic means at the lower part of the front of the cabinet.

55 While the design and construction at present illustrated and set forth is deemed preferable, it is obvious that as a result of

a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and 65 claimed.

In the drawings:

Figure 1 is a view in front elevation of the improved record cabinet, showing one of the doors thereof open, showing a plurality of records supported in the cabinet upon strands of cord in loop form.

Fig. 2 is a vertical sectional view on line 2—2 of Fig. 1.

Fig. 3 is a horizontal sectional view on line 3—3 of Fig. 1, transversely through the support for the strands of cord which support the records.

Fig. 4 is an enlarged detail perspective view of a fragmentary portion of the support, showing several of the strands of cord, and their eyes or loops connected to the hooks of the support.

Referring more especially to the drawings, 1 designates a cabinet as a whole, 85 which may be any suitable shape or construction, or may have any suitable configuration, preferably rectangular as illustrated. The inner faces of the sides of the cabinet have secured thereto supporting 90 pieces 2, and arranged in the cabinet is a transverse support 3, to which the strands of cord are connected. This support 3 has secured upon its upper edge near its opposite ends by means of screws plates 4. The 95 outer end portions of these plates are extended beyond the end parts of the supports 3 and engage recesses 5 of the supporting strips, thereby preventing displacement of the support. Furthermore, the ends of the 100 support are recessed as shown at 7, to conform to the supporting strips in cross-section. By virtue of the recesses engaging under the supporting strips, the support 3 is prevented from moving or tilting excessively.

The front face of the support is provided with a plurality of transverse ribs 8, and threaded through the support immediately under the strips 8 are hooks 9. The front 110 faces of the ribs are provided with numbers, preferably from 1 to 37 but not necessarily,

for it is obvious that the cabinet may be constructed to hold any number of records, for instance from fifty to a hundred or more and in such a case the numbers may be increased. These numbers are arranged directly over the hooks, to designate the hook. The support is provided with a plurality of openings or small apertures 10, through which strands of cord, or strands of any other suitable pliable material may be inserted, there being nuts or other suitable enlargements 11 formed on the ends of the cords 12 to prevent detachment of the cords. The other ends of the cords are connected at 13 to loops or eyes 14 of a plurality of body members or plates 15. These body members or plates 15 are numbered consecutively from 1 to 37 inclusive correspondingly with the numbers of the hooks, and are provided with eyes 16, which engage the hooks 9, that is to say after passing the strands of cord through the apertures or openings of the centers of the records, thereby supporting the records edgewise immediately above or on the bottom of the cabinet. It will be noted that the strands of cord after being passed through the central openings of the records and then connected to the hooks, form loops, upon which the records are suspended, just sufficiently to permit their marginal edges to be spaced slightly from or to engage (preferably the latter) the inclined bottom 18 of the cabinet.

35 The cabinet is provided with hinged doors 19, and suspended on hooks of the inner faces of both doors are index charts 20. These charts are lettered alphabetically, and when a record is placed in the cabinet, an entry is made on the index of the title of the record alphabetically, with the number of the cord on which the record is suspended following immediately after the name of the record on the index. For example, 40 should a record entitled "Somebody's Waiting" numbered 8 on the index chart be chosen, it is obvious that by removing the loop of the cord number 8, the desired record will roll down the inclined bottom 50 of the cabinet in a position to be grasped by the hand. The lower part of the forward portion of the cabinet has a front piece 21. The inner face of this front piece has a cushion 22 against which the 55 edge of the record contacts to prevent marring the edge of the record. The outer face of the front piece 21 is provided with several transversely arranged strands of elastic members 23. Suitable hooks 24 are carried 60 by the elastic members, and when any one of the records in the cabinet is removed, the loop of the numbered plate or body of the strand of cord is connected to one of the hooks, so that the cord will at all times 65 be in a convenient position to be grasped,

so as to be re-inserted in the central opening of the record, when restoring the record to its proper place. The hooks carried by the elastic members each consist of a wire bent to form eyes 25 through which the 70 elastic members pass.

The cords 12 are of different colors thereby greatly facilitating the return of the records to the cabinets. For instance, the cords are designed to be red, white and blue, 75 so that all red seal records can be attached to the red cords, while the blue ribbon records may be connected to the blue cords and other records can be attached to the white cords. When the records are replaced in 80 the cabinet they are reconnected to their respective cords, according to the name and number on the index and the number and color of the cord.

The invention having been set forth, what 85 is claimed as new and useful is:

1. The combination with a record cabinet, of a transverse support therein provided with a plurality of transverse ribs on one of its faces, a plurality of hooks carried by 90 the support immediately under the ribs, a plurality of strands of cord connected to the support and having eyes to be engaged with the hooks after the strands of cord are passed through the central openings of the 95 records.

2. The combination with a cabinet, of a support arranged transversely therein, flexible means depending from said support for individually and detachably suspending 100 a plurality of records from said support, said cabinet having an inclined bottom, whereby as any one of the records is detached from its suspension means, it will roll down the bottom in a position to be 105 grasped from the front of the cabinet.

3. The combination with a cabinet, of a support arranged transversely therein, means for detachably suspending a plurality of records from said support, said cabinet having an inclined bottom, whereby as any one of the records is detached from its suspension means, it will roll down the bottom in a position to be grasped from the front of the cabinet, the lower front portion of the cabinet 115 having means to which a portion of the suspension means may be connected temporarily while a chosen record is being played, so that the suspension means will be in a convenient position to be returned in engagement with 120 the central opening of the record.

4. The combination with a cabinet, of a support arranged transversely therein, means for detachably suspending a plurality of records from said support, said cabinet having an inclined bottom, whereby as any one of the records is detached from its suspension means, it will roll down the bottom in a position to be grasped from the front of the cabinet, and a cushioning front piece fixed 125 130

to the lower part of the front portion of the cabinet to cushion and limit the record as it rolls down the bottom, the outer face of the front piece having means to be engaged by 5 a part of one of the suspension means temporarily while a chosen record is being played so as to be in a convenient position to be re-inserted in the central opening of the record.

10 5. The combination with a cabinet, of a support arranged transversely in the upper part thereof, a plurality of pliable means carried by the support for suspending a plurality of records in the cabinet, said suspension means comprising a plurality of pliable strands, each having one end permanently attached to the support, and its other end terminating in a body provided with eyes, hooks carried by the support arranged in super-imposed rows, each to be engaged by an eye of one of the bodies of a strand, said strands being adapted to be passed through the central openings of the records and looped and having their eyes connected to the hooks for the suspension of the records.

25 6. The combination with a cabinet, of a bottom inclined from the rear of the cabinet downwardly toward the front thereof, a support arranged transversely of the upper part 30 of the cabinet, a plurality of means connected to the support for detachably suspending a plurality of records from the support, whereby their lower edges are held out of contact with the inclined bottom, whereby as 35 a part of any one of said means is detached from the support, the record carried by such means may be held to contact with the bottom and roll toward the front of the cabinet so as to be grasped.

40 7. The combination with a cabinet, of a bottom inclined from the back downwardly toward the front thereof, a support arranged transversely of the upper part of the cabinet, a plurality of means, each adapted to pass 45 through the central opening of a record and having a part attached to the support, and

another part detachably connected to the front part of the support in alinement with the first attached part, whereby the lower edge of the record is supported out of contact with the bottom, the last named attached part of the suspension means being adapted to be detached, whereby the record may contact with and roll along said bottom toward the front of the cabinet to be grasped. 50 55

8. The combination with a record receiving chamber having an inclined bottom, of a support in the upper part of the chamber and a plurality of individual means for suspending a plurality of records spaced above said inclined bottom, each of said means being detachable to release its respective record to permit it to roll upon the bottom to the front of the cabinet. 60

9. The combination with a record receiving chamber provided with an inclined member, of a plurality of means for suspending a plurality of records in parallel planes at right angles to said inclined member with their marginal edges spaced above said member, any one of said suspending means being releasable to permit any one of the records to drop upon and roll down the inclined member toward the front of the chamber. 65 70

10. The combination with a record receiving chamber having an inclined element, of a plurality of flexible means depending from the upper portion of the chamber and being adapted to pass individually through a plurality of records for supporting them in parallel planes at right angles to the inclined element with their marginal edges spaced from said element, each of said flexible means being detachably connected to the upper part of the chamber, whereby upon releasing any 80 85 one of said means its respective record will drop upon and roll down the inclined element toward the front of the chamber.

In testimony whereof I hereunto affix my signature.

HAROLD A. WIBERG.
